UNITED STATES PATENT OFFICE

HERMAN HAUG, OF NEW YORK, N. Y., ASSIGNOR TO ROSEMARY MFG. CO., OF ROANOKE RAPIDS, NORTH CAROLINA, A CORPORATION OF NORTH CAROLINA

DESIGN FOR A TEXTILE PANEL FOR A MATTRESS COVERING

Application filed March 22, 1930. Serial No. 35,001. Term of patent 3½ years.

To all whom it may concern:

Be it known that I, HERMAN HAUG, a citizen of the United States, residing at New York city, in the county and State of New York, have invented a new, original, and ornamental Design for Textile Panels for Mattress Coverings, of which the following is a specification, reference being had to the accompanying drawing, forming part thereof.

The drawing is a face view of a quarter section of the textile panel for covering a

mattress, indicated by dot and dash lines, the complete panel comprising four such portions woven in meeting or matching relation. That portion of the design extending beyond the dot and dash lines indicates the relation that the other sections bear to the one illustrated in detail.

I claim:

The ornamental design for a textile panel for a mattress covering, as shown and described.

HERMAN HAUG.
